PAGE 3

FIG. 10

FIG. 7

FIG. 1 is a rear perspective view of a golf club putter head showing my new design;

FIG. 2 is a top plan view thereof;

FIG. 3 is a bottom plan view thereof;

FIG. 4 is a right side elevational view thereof, the opposite view being a substantial mirror image;

FIG. 5 is a front elevational view thereof; and

FIG. 6 is a rear elevational view;

FIG. 7 is another embodiment of FIG. 1 wherein the edges and corners are rounded;

FIG. 8 is a top plan view of FIG. 7;

FIG. 9 is a bottom plan view of FIG. 7;

FIG. 10 is a right side elevational view of FIG. 7, the opposite side being a substantial mirror image;

FIG. 11 is a front elevational view of FIG. 7; and

FIG. 12 is a rear elevational view of FIG. 7.

I claim:

The ornamental design for a golf club putter head, as shown and described.
